(57) **CLAIM**

The ornamental design for an aircraft, as shown and described

DESCRIPTION

FIG. 1 is an isometric view of the aircraft of the present invention, shown from a vantage point to the front, the right, and above the aircraft;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

Phantom lining, where utilized, is for illustrative purposes only and is not intended to limit the claimed design to the features shown in phantom.
